A. D. Jackson
ATTORNEY.

UNITED STATES PATENT OFFICE

FRENCH B. WILLIAMS, OF FORT WORTH, TEXAS, ASSIGNOR, BY DIRECT AND MESNE ASSIGNMENTS, OF FIVE-FORTIETHS TO J. H. CLARK, FIVE-FORTIETHS TO A. P. BARKER, FOUR-FORTIETHS TO H. T. PANGBURN, AND TWENTY-FORTIETHS TO C. R. PRESSLEY, ALL OF FORT WORTH, TEXAS

COTTON GIN

Application filed October 17, 1927. Serial No. 226,616.

My invention relates to cotton gins and more particularly to improvements in ribs for cotton gins; and the object is to provide revolving ribs and other ribs which co-operate with the revolving ribs which will prevent the choking of the ribs and saws and which will reduce the power required to run the gin and make it possible for the gin to run faster because it prevents the cotton from crowding and rubbing against the saws and ribs and for these reasons the improvements make the operation of the gin more economical. Another advantage is that the fire hazard is reduced by preventing friction of the saws and ribs against the cotton. It has been discovered that the cause of fire in many instances is the friction of the cotton and saws and the particular location of the trouble is the cotton that becomes hung on the ribs and bears against the saws on the undersides of the ribs, that is after the saws pass through the ribs, the saws rub against the cotton that is clinging to the ribs and this is where the fire originates. The object is to provide revolving ribs that will throw the cotton roll back away from the points where the saws pass through the stationary ribs and to change the shapes of the stationary ribs to co-operate with the revolving ribs. Other objects and advantages will be fully explained in the following description and the invention will be more particularly pointed out in the claims.

Reference is had to the accompanying drawings which form a part of this application.

Fig. 1 is a vertical section of a gin stand, showing the disposition of the revolving ribs and the stationary ribs.

Fig. 2 is a front elevation of the revolving ribs in part on an enlarged scale, also showing the position of the stationary ribs relative to the revolving ribs.

Fig. 3 is a side elevation of one of the stationary ribs.

Similar characters of reference are used to indicate the same parts throughout the several views.

A gin stand of ordinary type is shown in the drawings provided with the improve-

ments and saws and a brush drum. The gin has the usual roll box 1, saws 2, and brush drum 3, and other parts not necessary to be described in this application. The gin stand has a saw shaft 4 for the saws 2. The stationary ribs 5 are attached at their lower ends to the frame member 6. At their upper ends the ribs are attached to the rear of the frame member 7 instead of the front. The ribs 5 are spaced apart for the passage of the saws 2 in the usual manner. Each rib 5 has an arcuated divider 8 which is curved slightly to conform approximately to the curvature of the roll box for the purpose of aiding in keeping the roll of cotton intact. From the point 8 the ribs have members 9 curved downwardly and then upwardly and attached to the frame member 7, the object being to position the parts of the ribs through which the saw teeth pass as far as possible from the roll of cotton. Another object is to provide a space for mounting the revolving ribs 10 which are rigid with a shaft 11. The saws 2 and the revolving ribs 10 revolve in the directions indicated by arrow heads. The function of the revolving ribs 10 is to brush the cotton away from that portion of the ribs 9 through which the saws pass and to keep the unginned cotton pushed or pressed into the cotton roll which is revolving in the roll box. The unginned cotton is thus kept away from the saw passage through the ribs 9 so that nothing but lint cotton will be carried by the saws through the ribs 9. The object is to prevent the clogging of the passage through the ribs with seed cotton and seed and parts of branches of cotton stalks and to keep the saws clean except the lint cotton carried thereby to be removed by the brush drum 3 or other means. The curvature of the rib members 9 should be approximately that of the curvature of the revolving ribs 10. The revolving ribs 10 are driven by a belt 12 which is driven by a pulley 13 mounted on the shaft 4. The seed separating means 14 are of the usual type and need not be described herein.

The stationary ribs 9 and the revolving ribs, when arranged as above set forth, per-

form the functions set forth in the first paragraph of this specification on page 1.

What I claim, is,—

1. In a cotton gin provided with a gang of 5 saws and a roll box; stationary ribs and revolving ribs projecting between said saws and positioned above said saws and backwardly of said roll box, said stationary ribs being curved under and behind said revolving ribs 10 and cooperating with said revolving ribs to space the point of passage of the saws between said stationary ribs away from the roll formed in the roll box.
2. In a cotton gin provided with a gang of 15 saws and a roll box; stationary ribs and revolving ribs positioned above said saws and backwardly of said roll box and projecting between said saws, said revolving ribs serving to brush unginned cotton away from said 20 stationary ribs prior to the passage of the saw teeth between said stationary ribs.
3. In a cotton gin provided with a gang of 25 saws and a roll box; stationary ribs and revolving ribs positioned above said saws and backwardly of said roll box and projecting between said saws, said stationary ribs having arcuate members projecting partly in front of said revolving members and co-operating with said revolving members for 30 causing unginned cotton to cling to the roll of cotton in said roll box until it is ginned.
4. In a cotton gin provided with a gang of 35 saws and a roll box; stationary ribs projecting between said saws and revolving ribs positioned above said saws and backwardly of said roll box and projecting between said saws, arcuate members formed on said stationary members and co-operating with said revolving ribs to cause the unginned cotton 40 to cling to the roll of cotton in said roll box until it is ginned and said stationary ribs being curved partly about said revolving ribs for spacing the point of passage of the saw teeth through the stationary ribs away from 45 the roll of unginned cotton.
5. In a cotton gin the combination with a 50 frame, of a series of rotary saws journaled in said frame, a series of rotary ribs revolving between said saws and journaled in said frame above said saws, a portion of each of said ribs projecting downwardly below the periphery of one of said saws adjacent thereto, a stationary rib between successive saws having its upper and lower ends supported 55 on said frame respectively above and below said saws at points substantially diametrically opposite, each of said stationary ribs having a curved lower portion conforming substantially to the curved edge of said saw 60 and having a curved upper portion in the same plane with and concentric with each of said rotary ribs, said curved upper portion being spaced from but adjacent to substantially half of the periphery of each of said 65 rotary ribs including that portion of the pe-

riphery of said rotary rib projecting downwardly below the periphery of said saw adjacent thereto.

6. In a cotton gin, the combination with a frame, of a series of rotary saws journaled in said frame, a series of rotary ribs revolving between portions of said saws and journaled in said frame above said saws, a portion of each of said ribs projecting downwardly lower than the peripheries of two of said saws adjacent thereto, a stationary rib between successive saws having its upper and lower ends supported on said frame respectively above and below said saws at points substantially diametrically opposite, each of said stationary ribs having a curved lower portion conforming substantially to the curved edges of two of said saws adjacent thereto and having a curved upper portion in the same plane with and concentric with each of said rotary ribs, said curved upper portion, being spaced from but adjacent to substantially half of the periphery of the cooperating rotary rib adjacent thereto including that portion of the periphery of said rotary rib projecting downwardly lower than the peripheries of two of said saws adjacent thereto.

7. In a cotton gin provided with a gang of 95 saws and a roll box; stationary ribs and revolving ribs projecting between said saws and positioned back of said roll box, said stationary ribs being curved under and behind said revolving ribs and cooperating with said revolving ribs to space the points 100 where said saws leave said stationary ribs away from the roll formed in said roll box.

In testimony whereof, I set my hand this 11th day of October, 1927.
